(57) **CLAIM**

The ornamental design for a dress with anatomy enhancing shading, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

FIG. 1 is a front view of a dress with anatomy enhancing shading showing a new design.

FIG. 2 is a back view of a dress with anatomy enhancing shading showing a new design.

FIG. 3 is a left side view of a dress with anatomy enhancing shading showing a new design.

FIG. 4 is a right side view of a dress with anatomy enhancing shading showing a new design.

FIG. 5 is a top view of a dress with anatomy enhancing shading showing a new design; and,

FIG. 6 is a bottom view of a dress with anatomy enhancing shading showing a new design.

The dashed lines showing the dress, stitching, and other details on the dress forms no part of the claimed design. The surface indicia (or shading) shown forms the claimed subject matter. The brightness of the surface indicia on the dress is indicated by the darkness of the surface indicia in the figure.
